(57) **CLAIM**

The ornamental design for a dash cam as shown and described.

DESCRIPTION

FIG 1 is a front perspective view of a dash cam showing my new design;

FIG. 2 is a back perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof; and,

FIG. 9 is an enlarged view taken from encircled portion labeled, “9,” in FIG. 1.

The dashed-dot lines form the boundary of the enlarged portion view of FIG. 9 in FIGS. 1 and 9 and form no part of the claimed design. The even dashed broken lines shown in the drawings are included for the purpose of illustrating portions of the dash cam that form no part of the claimed design.
